(57) **CLAIM**

The ornamental design for buttons for a computing device, as shown and described.

DESCRIPTION

FIG. 1 is a front plan view of the buttons for a computing device;

FIG. 2 is a front plan view thereof with a computing device shown in broken lines; and,

FIG. 3 is a front plan view thereof with a different computing device shown in broken lines.

The broken line showing of a computing device in FIG. 2 and FIG. 3 is included for the purpose of illustrating the design as implemented on a computing device and forms no part of the claimed design. The broken line showing of the areas within the buttons shows the boundaries of unclaimed areas.
